(57) **CLAIM**

The ornamental design for a catheter tip with electrode panel(s), as shown and described.

DESCRIPTION

FIG. 1 is a front view of catheter tip with electrode panel(s) showing only one panel;

FIG. 2 is a perspective view thereof;

FIG. 3 is a perspective view of a catheter tip with electrode panel(s);

FIG. 4 is a front view thereof;

FIG. 5 is a rear view thereof; and,

FIG. 6 is a side view thereof.

The broken lines in the drawings depict environmental subject matter only and form no part of the claimed design.
